UNITED STATES PATENT OFFICE.

ALGERMONT H. WALDO, OF ST. PAUL, MINNESOTA.

DESIGN FOR A RUG.

55,907.

Specification for Design. Patented July 20, 1920.

Application filed April 9, 1920. Serial No. 372,651. Term of patent 3½ years.

To all whom it may concern:

Be it known that I, ALGERMONT H. WALDO, a citizen of the United States, residing at St. Paul, in the county of Ramsey and State of Minnesota, have invented a new, original, and ornamental Design for a Rug, of which the following is a specification, reference being had to the accompanying drawing, forming a part thereof, and wherein:—

The figure is a plan view of a rug showing my new design.

I claim:

The ornamental design for a rug, as shown.

Signed at St. Paul, Minnesota, April 2nd, 1920.

ALGERMONT H. WALDO.
